UNITED STATES PATENT OFFICE.

WILLIAM R. LANDFEAR, OF BROOKLYN, NEW YORK.

LABEL PRINTING AND PERFORATING MACHINE.

SPECIFICATION forming part of Letters Patent No. 288,349, dated November 13, 1883.

Application filed April 7, 1883. (No model.)

To all whom it may concern:

Be it known that I, WILLIAM R. LANDFEAR, of the city of Brooklyn, in the county of Kings and State of New York, have invented a new and useful Improvement in Label Printing and Perforating Machines, of which the following is a specification.

My invention relates to machines for producing strips with labels printed on them in gold and a color or colors, and from which the labels are subsequently cut or punched by a second machine; and the object of my invention is to provide a very effective machine for applying the gold-size and gold-powder, for brushing off the surplus powder, for printing in a color or colors without the liability of any deposit of bronze on that printing, and for perforating or cutting holes in the strip to receive the register-pins in the machine where-
10 in the labels are punched or cut from the strip, but without, however, wholly removing from the holes the portions cut out, so that they will not fall into and become mixed with the bronze-powder and interfere with its applica-
15 tion.

The invention consists in the combination, in a machine for printing and perforating strips of labels, of a printing-cylinder and an impression-cylinder provided with punches 30 and dies adapted to cut a series of holes in the strip without entirely freeing the paper from such holes.

The invention also consists in a novel construction of the punches and dies, whereby 35 they are enabled to perforate the strip without removing the paper from the holes.

The invention also consists in the combination, with an impression-cylinder and two printing-cylinders, one of which prints the labels in gold-size, of an apparatus for applying 40 bronze-powder, interposed between the two printing-cylinders, and serving to apply bronze-powder to the impressions printed in gold-size and before the strips are printed in color.

The invention also consists in the combination, in a printing-machine of the kind described, of side frames and stretchers connecting them, shafts journaled in said side frames 50 and projecting beyond the frame at one end, an impression-cylinder and two printing-cyl-

inders secured upon the projecting portions of said shafts and outside the frame, and a bronzing apparatus interposed between said printing-cylinders, and serving to apply 55 bronze-powder to the impressions printed in gold-size and before they are printed in color.

In the accompanying drawings, Figure 1 is an end elevation of a machine embodying my invention. Fig. 2 is a side elevation thereof, 60 a portion of the bronzing apparatus being shown in section. Fig. 3 is a detail sectional view of a portion of the impression-cylinder and one of the printing-cylinders on a larger scale. Fig. 4 is a perspective view of one of 65 the dies detached from the cylinder, and Fig. 5 is a portion of one of the label-strips after printing.

Similar letters of reference designate corresponding parts in all the figures. 70

A A designate the two side frames of the machine, which are connected by suitable stretchers, A'.

B C D designate three shafts which are journaled in the side frames, and which project at one end beyond the same. The shaft B as here shown constitutes the driving-shaft, and carries fast and loose pulleys B' B², over which a driving-belt may run. Upon the shaft B is also mounted a spur-gear wheel, B³, and on 80 the shafts C D are mounted pinions C' D', which engage with the wheel B³ and receive motion therefrom. 75

Upon the projecting end of the shaft B, and outside the side frame, A, is secured the impression-cylinder E, and in the same vertical plane therewith, and on the projecting ends of the shafts C D, are printing-cylinders F G. The impression-cylinder E and the printing-cylinders F G severally rotate in the direction indicated by the arrows in Fig. 2. 85

Upon the periphery of each cylinder F G are a number of printing-forms, a, which, as here shown, consist of plugs inserted into the cylinder and secured by set-screws b, and each printing-cylinder is provided with inking-rollers c and any common form of ink-fountain and doctor-rolls. 95

The entire inking apparatus is not shown, as it is not thought necessary. 100

The strip of paper, d, to be printed is drawn from any suitable reel or drum, and passes

over a guide, *e*, and thence around the impression-cylinder *E*, where it receives first an impression of gold-size from the forms on the cylinder *F*, and finally an impression in color from the forms on the cylinder *G*, after which it passes to a take-up roll or drum, *f*, (shown in Fig. 2.) After the strip passes the cylinder *F*, and before it reaches the cylinder *G*, it receives the bronze-powder. In the same vertical plane as the cylinders, and below the cylinder *E*, is a bronzing wheel or roll, *H*, which is mounted on a shaft, *H'*, and which is covered with felt or other soft material. The wheel or roll *H* is arranged in a powder box or casing, *H''*, and is turned slowly and in contact with the strip *d*, to apply the powder to the impressions of gold-size made by the cylinder *F*. The wheel or roll derives motion from the main shaft *B* through a belt, *g*, passing round a pulley, *g'*, 20 on the shaft *H'*.

Beyond the wheel or roll *H* are arranged a number of brushes, *I*, four being here shown. They are secured to shafts *I'*, which are journaled in the side frames, *A*, and are rotated 25 rapidly by a belt, *I''*, which passes round a pulley, *I'''*, on the main shaft *B*, and embraces all the spindles and pulleys *h* with which they are provided. As the brushes *I* are rotated they remove all the surplus bronze-powder from the 30 strip *d*, and it is collected in the casing *J*, which surrounds the brushes.

The printed labels are shown in Fig. 5 as well as they can be in black and white. The lines and letters are printed in one color, and the 35 gold is represented by dots. In the strip *d* are represented a row of small holes, *i*, which receive the register-pins in the machine, whereby the labels are cut or punched from the strips, so as to insure the perfect register of the 40 punches whereby the labels are cut out with the impressions.

As shown in Fig. 5, the circles representing the holes *i* are not complete, and the break in the line indicates that the portion of paper 45 cut out is not entirely freed from the strip, but remains attached thereto. If the portions of paper cut out were entirely freed, they would drop into the bronze-powder, and might produce imperfect work by becoming stuck 50 upon the labels. The holes *i* are cut by punches *j* in the periphery of the printing-cylinder *G*, which operate in connection with the dies *k*, inserted in the periphery of the impression-cylinder *E*. As here represented, and as best 55 shown in Fig. 3, the cylinder *G* has a rim or flange, *G'*, and the punches *j* are screwed into said rim or flange from the inner side. The face of each die *k* has in it a notch or depression, *k'*, (shown in Fig. 4,) and by the action 60 of the punch the paper is cut, except over the

notch, and consequently each piece of paper cut to form the hole is left attached by a portion equal to the width of the notch. The register-pins in the machine which is employed to punch or cut the labels from the 65 strip will enter the holes *i* as well as if the paper were removed entirely from them in the act of punching the holes, and the pieces of paper will not drop into the casing *J* and become mixed with the bronze-powder. 70

If desired, more than one color-printing cylinder *G* may be used, and, if so, the holes *i* will be punched by the last cylinder.

The arrangement of the bronzing apparatus between the printing-cylinders which 75 print in gold-size and in color is very desirable, because there is no liability of the bronze-powder being deposited on the color-printing, as there would be if the powder were applied after the printing in color and while the 80 impressions in color were still damp.

What I claim as my invention, and desire to secure by Letters Patent, is—

1. The combination, in a machine for printing and perforating strips of labels, of a printing-cylinder and an impression-cylinder provided with punches and dies adapted to cut a series of holes in the strip without entirely freeing the paper cut in forming the holes from the strip, substantially as and for the 90 purpose described.

2. The combination of the impression-cylinder *E* and the printing-cylinder *G*, one provided with punches *j* and the other with dies *k*, having notches *k'* in their faces, substantially as and for the purpose specified. 95

3. The combination, in a machine for printing labels in strips, with an impression-cylinder and two printing-cylinders, one of which prints the labels in gold-size, of an apparatus 100 for applying bronze-powder, interposed between the two printing-cylinders, and serving to apply powder to the impressions printed in gold-size and before the strip is printed in colors, substantially as specified. 105

4. The combination, in a machine for printing labels in strips, of side frames and stretchers connecting them, shafts journaled in said frames and projecting beyond the frame at one end, an impression-cylinder, and two 110 printing-cylinders secured upon the projecting portions of said shafts and outside the frame, one of said printing-cylinders serving to print in gold-size, and a bronzing apparatus interposed between the two printing-cylinders, substantially as described. 115
